UNITED STATES PATENT OFFICE.

WALTER SCHAFFER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

ARRANGEMENT FOR GENERATING AUDIBLE FREQUENCIES IN HIGH-FREQUENCY SIGNALING.

Application filed June 5, 1924, Serial No. 717,932, and in Germany June 27, 1923.

My invention relates to an arrangement for generating audible frequencies for modulating a carrier wave in signaling systems.

It has for its object to provide such an arrangement which will produce an audible frequency by means of two circuits, one of which contains a microphone and the other a telephone, the circuits being electrically coupled and the microphone and telephone being acoustically coupled.

Another object of the invention is to provide a similar arrangement employing an additional heterodyning circuit which can be used to change the frequency of the audible signal.

Other objects will be apparent to those skilled in the art from the following description and claims when considered with the accompanying drawing, in which the single figure represents a circuit embodying my invention.

There are already transmitting arrangements for wireless telegraphy which use radiofrequency vacuum tube transmitters, on the grid circuits of which are superimposed alternating currents of audible frequency. The generators of audible frequency have been, till now, buzzers, vacuum tubes oscillating in an audible frequency, commutators of direct current dynamos, the said commutators consisting of a great number of segments, and various other devices.

All these known arrangements require a greater or smaller quantity of energy, for the generation of audible frequency and furthermore complicated and expensive auxiliary apparatus.

The present invention relates to a transmitter of audible frequency, which is generated in a very simple manner. The invention uses for this purpose the known acoustic phenomenon which occurs if a circuit containing a telephone is suitably coupled to a microphone circuit and the microphone is acoustically coupled to a telephone. Under these conditions an intensive musical note is generated, the frequency of which depends on the natural vibration of the telephone.

The drawing shows an application of this invention which may be employed for any telephone connection using separately excited or self-excited transmitting vacuum tubes. A is the aerial and is coupled to the

oscillator tube R¹. The aerial circuit is grounded through coil 9 for a purpose 55 explained hereinafter.

The output circuit of the tubes R¹ comprises condenser 1, coil 2 and condenser 3. The input circuit is connected across condenser 3. The plate current of tube R¹ is 60 supplied by means of B-battery 4 through coil 5 and thermionic tube R², which tube operates as a variable resistance in the plate circuit of tube R¹, the resistance of tube R² being controlled by the potential on 65 its grid. Connected to the input circuit of the tube R² is coil 6. Coupled to coil 6 is coil 10 which is in circuit with microphone M, battery 8, and key S, comprising the microphone circuit. 70

Acoustically coupled to microphone M is telephone T. Telephone T is in an aperiodic telephone circuit, which is coupled to coil 9 in the antenna circuit by means of coil 7. In this circuit is also a rectifier K. 75 Connected across telephone T is condenser 11.

The acoustic and electrical coupling of the telephone and microphone circuits gives rise to a sustained audible oscillation, the 80 frequency of which is determined by the acoustic properties and arrangement of the microphone M and telephone T. Key S is operated according to the signal it is desired to transmit which may be in the form of the 96 usual Morse characters.

It will be easily understood that when the key S is operated an audible frequency is generated which is impressed upon the grid circuit of tube R² and varies the resistance 95 in the plate circuit of tube R¹ thereby varying the amplitude of the carrier wave generated by the oscillating tube R¹ in accordance with the signal which is being sent.

It will be easily understood that the audible oscillations are generated, when key S is closed by the regenerative effect of the modulated carrier wave being fed back into the telephone circuit by means of coupling coils 7 and 9. The modulated carrier wave, 105 after being rectified by rectifier K is impressed on telephone T in phase with the audible oscillations which are being generated by telephone T, and reinforces them.

If it is desired to vary the audible frequency this can be done by means of a 110

heterodyne circuit U connected in parallel to the telephone T. The oscillations of the heterodyning circuit will then be combined with the sustained oscillations of the microphone-telephone circuits to produce the new and desired audible frequency.

It will easily be understood by those skilled in the art that the sending key S may be in the telephone circuit instead of in the microphone circuit.

Having described a single embodiment of my invention, I am entitled to all modifications thereof as fairly come within the scope of the following claims.

Having described my invention, what I claim is:

1. An arrangement for transmitting signals by means of a carrier wave, comprising a transmitting circuit, a source of carrier waves coupled thereto, a first circuit containing a first electro-acoustic device, a second circuit containing a second electro-acoustic device, said first and second electro-acoustic devices being acoustically coupled, means for coupling said first and second circuits to obtain sustained oscillations, and means for modulating the carrier wave with said sustained oscillations.

2. An arrangement for transmitting signals by means of a carrier wave, comprising a transmitting circuit, a source of carrier waves coupled thereto, a first circuit containing a microphone, a second circuit containing a telephone and rectifier, said second circuit being coupled to said transmitting circuit, said microphone being acoustically coupled to said telephone and means for modulating the carrier wave by oscillations generated in said first circuit.

3. An arrangement for transmitting signals by means of a carrier wave, comprising a transmitting circuit, a source of carrier waves coupled thereto, a first circuit containing a first electro-acoustic device, a second circuit containing a second electro-acoustic device, said first and second electro-acoustic devices being acoustically coupled, means for coupling said first and second circuits to obtain sustained oscillations, heterodyne means coupled to one of said first and second circuits for producing a beat with said sustained oscillations, and means for modulating the carrier wave with said beat.

4. In combination, a transmitting key

associated with audio frequency responsive means, means for transmitting a carrier wave, means for modulating the transmitting means by the audio frequency and means for reacting on the audio frequency means from effects produced by the audio means on the modulating means to accentuate the audio frequency.

5. In combination, a transmitting key associated with audio frequency responsive means, means for transmitting a carrier wave, means for modulating the transmitting means by the audio frequency and means for reacting on the audio frequency means from effects produced by the audio means on the modulating means to accentuate the audio frequency, whereby the transmitting key causes the audio means to become operative and inoperative alternately according to the signal desired to be transmitted.

6. In combination, means for transmitting a carrier wave, audio frequency means, means for modulating the transmitting means by the audio frequency means and means for reacting on the audio frequency means from effects produced by the audio means on the modulating means to accentuate the audio frequency.

7. In combination, means for transmitting a carrier wave, audio frequency means, means for modulating the transmitting means by the audio frequency means and means for reacting on the audio frequency means from effects produced by the audio means on the modulating means to accentuate the audio frequency, and means for producing a beat note with the audio frequency.

8. In combination, means for transmitting a carrier wave, secondary frequency means, means for modulating the transmitting means by the secondary frequency means and means for reacting on the secondary frequency means from effects produced by the secondary means on the modulating means to accentuate the secondary frequency, means for combining with the secondary frequency means, oscillations generated by a heterodyning circuit, whereby the natural oscillations of the secondary frequency combines with the heterodyne set of oscillations to produce a beat note thereby attaining a larger note-scale.

WALTER SCHAFFER.
